UNITED STATES PATENT OFFICE.

WILLIAM JOHN WILGUS, OF YONKERS, AND FRANK JULIAN SPRAGUE, OF NEW YORK, N. Y.

THIRD RAIL.

No. 908,180.

Specification of Letters Patent.

Patented Dec. 29, 1908.

Application filed May 27, 1905. Serial No. 262,626.

To all whom it may concern:

Be it known that we, WILLIAM JOHN WILGUS, of the city of Yonkers, in the county of Westchester and State of New York, and 5 FRANK JULIAN SPRAGUE, of the city, county, and State of New York, both citizens of the United States of America, have invented certain new and useful Improvements in Third Rails, of which the following is a specification.

10 The object of our invention is to produce an under-contact conductor, particularly applicable as an inverted third-rail with suitable supports from which it is a thoroughly insulated, and with a suitable protective cover or sheathing throughout its length, the whole being combined to form an under-contact conductor with a structure having the following characteristics, to wit: 1. The 15 cover acts as a protection, insulator and splice. 2. The distribution of the joints is such that the rail and cover afford support each to the other, and provide for the adjustment of the rail to varying temperatures and stresses. 3. The relation of the 20 parts is simple, thus facilitating, and minimizing cost of construction and repair, and enabling the constructor to keep the structure within the restricted limits of clearances 25 for all kinds of rolling stock. 4. The entire electrified part of the structure is shielded from accidental contact and grounding by trespassers and employees. 5. Pockets are avoided where snow, sleet or other matter 30 may accumulate and cause trouble. 6. The structure is so shaped that icicles cannot form from the contact surface of the rail, but only at a distance from the rail, where they will be readily cut off by the contact 35 shoe, thus insuring greater certainty of continuity of contact and less likelihood of flashing. 7. The structure is so arranged that leakage and consequent possible 40 charring of the wood covering near and at an accidentally grounded support is made impossible by the interposition of a moisture-proof and fire-proof insulating section at the support. 8. The system is so constructed 45 that it is adaptable to curved as well as straight lines of track, and can be fitted at frogs and switches in the ordinary course of track laying. 9. Alinement of the rail independently of vertical alinement of the 50 brackets is secured without straining at the connections. 10. The requisite mechanical strength and insulation is brought within a

limited space and with few parts of materials which can be readily obtained.

In order to attain the foregoing objects, we have invented an under-contact rail structure wherein an under-contact rail is supported by brackets, preferably loosely between holding-blocks of tough, moisture-proof insulating material which may be a refractory material with high insulating 60 properties, such as reconstructed granite, which are supported at the brackets and inclose and protect the sides and top of the rail at the brackets. The rail is provided through its entire length between the holding-blocks with a protecting and insulating cover or sheathing made in strips and supported by the rail, the material being such that the strips can be conformed to any 65 curvature in the track.

The drawings have been carefully made to scale, so as to show the adaptation of our structure to standard steam and electric railway practice under the principal conditions that require consideration.

In the accompanying nine sheets of drawings, which form a part of this specification, Figure 1 is a cross section of a two-track road, each track of which is equipped with an under-contact rail embodying our invention, and also showing by dotted lines the requisite clearance for maximum equipment permitted on the road. Fig. 2 is an elevation and Fig. 3 is a top view showing a section of the under-contact rail. Fig. 4 shows 80 in plan a portion of a four-track road with the preferred disposition of under-contact conductors and brackets with respect to the road as a whole. Fig. 5 is a section of the under-contact rail taken through the wood 85 protection on the line B—B of Fig. 6. Fig. 6 is an elevation and Fig. 7 is a top view of the under-contact rail at one of the brackets. Fig. 8 is a section of the under-contact rail 90 taken on the line A—A of Fig. 6 at the edge of an insulating block, and also of the contiguous track-rail showing their relation to each other and to the maximum equipment line. Fig. 9 is a section taken at the line 95 D—D of Fig. 15 through the wood protection of two under-contact rails meeting at a frog and supported from a special form of bracket. Fig. 10 is an edge view and Fig. 11 is a top view of this form of bracket, the iron contact rails and insulating parts being 100 omitted. Fig. 12 is a section of the structure of Fig. 9 taken at the line D'—D' of 105

Fig. 15 at the edge of the insulating block and showing the relation to a contiguous track-rail and the maximum equipment lines of both tracks. Fig. 13 is a side view and 5 end view showing the modified forms of wood protection or sheathing strips and refractory or other tough insulating blocks employed at frogs. Fig. 14 is a side view and end view of the modified form of iron contact rail, and 10 Fig. 15 is an elevation of these parts assembled. Figs. 16, 17 and 18 are sections drawn to a larger scale of the under-contact rail at a frog taken at the lines E—E, D—D, and C—C respectively. Figs. 19 and 20 comprise side, top and section views of a block 15 clamp. Figs. 21, 22 and 23 are respectively sections on the line F—F of Fig. 22, an elevation and a top view of an insulating block. Figs. 24 and 25 are side and front views of a 20 wood protection clamp. Fig. 26 is a section on the line B—B of Fig. 6, showing the outline of two adjacent wood protecting strips. Figs. 27 and 28 are respectively an elevation 25 broken away and a sectional view on the line G—G of Fig. 27, showing an improved form of telescoping electrical rail bond. Figs. 29 and 30 are similar views showing a slightly modified form of electrical rail bond. Fig. 31 is a 30 side elevation with the wood protection removed, showing a flexible bond connection. Fig. 32 is a section on the line J—J of Fig. 31. Figs. 33 and 34 are respectively an elevation 35 and a section on the line K—K of Fig. 33, showing the manner in which the wood protection is mortised when this form of bond is employed. Figs. 35 and 36 are views similar to Figs. 31 and 32, the latter being a section on the line L—L of Fig. 35, showing the addition of fish-plates. Figs. 37 and 38 are 40 respectively a side elevation and a section on the line M—M of Fig. 37, showing a modified form of wood protection in three instead of two parts. Figs. 39 and 40 are respectively a section on the line N—N of Fig. 40 and a 45 side elevation, showing a modified form of insulating holding-block in three pieces. Fig. 41 illustrates a plan for the third-rail construction at a cross-over between four tracks. Fig. 42 illustrates a plan for the 50 third-rail construction at a cross-over between four tracks where space is more limited. Fig. 43 illustrates a plan for the third-rail construction with cross-overs from an intermediate track to each of two adjacent 55 tracks for the same direction of travel on the intermediate track. Fig. 44 illustrates a plan for the third-rail construction with cross-overs from an intermediate track to each of two adjacent tracks for the same direction of travel on the intermediate track 60 where space is more limited.

An iron contact rail *a*, and cast-iron upright supporting brackets *b*, are employed, the brackets being evenly spaced at intervals 65 of one-third of the rail-lengths and so posi-

tioned with reference to the rail that the points of meeting of consecutive rail-lengths will lie midway between adjacent brackets. As the rail is conveniently obtained in thirty-three foot sections, there will be in usual 70 and ordinary practice one bracket for every eleven feet of rail. The brackets are spiked to the tops and near the ends of ties of extra length.

A pair of holding-blocks *c c* are mounted at 75 each bracket and the rail is suspended from the bracket between these holding-blocks. The brackets are each provided with a face against which rests the outer face of the block of the pair farthest away from the 80 track. A horizontal tongue *d* is positioned upon this face of the bracket and enters but does not closely fit a corresponding groove in the block, thus preventing the block from sliding down the face. 85

The pair of blocks are held against the face of each bracket by a steel clamp-hook *e*, the hooked end of which enters but does not closely fit a groove in the track-side block of the pair, and overlies the top of both blocks, 90 where it lies in a groove in the top of the pair of blocks, whereby endwise movement of the blocks is prevented. The structure also enables the top of the clamp-hook to be brought down to the level of the top of the blocks, 95 and by making these clamp-hooks of steel, we avoid the bulky top encroaching on the clearance line of equipment which would be required if the whole structure were of cast-iron. 100

The stem of the hook passes loosely through a hole in the upper end of the bracket to which the hook is drawn by a nut. The blocks meet above the rail and the clamp holds the blocks securely to each other and 105 to the rail and the bracket. But the blocks conform loosely to the rail, and because of this and other features of construction elsewhere pointed out, and further, because the clamp-hook or hook-bolt employed has 110 some flexibility, there results a certain vertical play between the rail and the brackets to allow for the displacement of any bracket by reason of insufficient ballasting of the tie to which it is spiked and consequent 115 depression under heavy traffic or because of departure of the track from correct alignment, whether temporary or permanent, and from whatever cause. By reason of the looseness of the support, the weight of the 120 rail is solely relied upon to oppose the upward thrust of the contact shoe. The grooving and other features of the blocks are alike, so that the blocks are interchangeable. 125

Between the points of protection and support of the rail at the brackets by the moisture-proof blocks, the rail in turn supports and is protected by a sheathing formed of strips of wood *f f* of about the same cross-sectional form as the blocks. Wood is se- 130

lected because of its tensile strength, and because it can be readily adapted to curves, the wood being saw-cut when necessary. The wood is held in place when practicable by 5 clamps *g g* which embrace the tops and sides of the protecting strips, such methods of holding being preferable to bolts because they are adequately insulated from the rail by being entirely outside the wood and open to inspection. Modification of this construction is, however, permitted at frogs, where bolts *h h* are substituted for the clamps *g g*. This is because of the diminished vertical thickness of the structure owing to the necessity 10 of beveling the contact surface for the entrance of shoes and at the same time maintaining clearances at the top. The bolts also prevent end-displacement of the protecting strips. Along regular track such displacement is prevented by the abutment of the strips at each end with the blocks which are held at the brackets.

It will be seen that the blocks and wood strips form a continuous protection for the 25 sides and top, made up of abutting alternately short and long sections of insulation, the former being preferably practically fire-proof, substantially impervious to moisture and of high insulation, and the latter possessing tensile strength, cheapness and flexibility. The two together form a protective sheath of substantially unbroken line, so that any equipment objects, such as loose bolts or springs, or material carried by the equipment 30 and happening to lie outside the equipment-line and to touch the third-rail structure, may drag along the top or inner side without liability to cause injury before discovery.

In Figs. 27 and 28 are illustrated two 40 forms of telescoping electrical bond in the form of a pair of plugs which enters the ends of both rails. Holes are drilled in the abutting ends of the rails, then reamed, and while bright, sleeves *k* of low oxidizable metal, as 45 bronze or aluminum, are driven into the holes. Inside of these are plugs *l*, preferably of the same metal as the sleeves, to prevent electrolysis. The plugs snugly fit the sleeves to insure good electrical contact, but 50 so as to slide to compensate for variations in the lengths of rails at varying temperatures. The lower plug of the two is of a modified construction, consisting in the provision of a plug of tubular form which is slotted along 55 one side, thereby imparting a greater range of elasticity to the plug so that the desired closeness of fit between the plug and the sleeves can be secured with less machining. By using two plugs at the abutting ends of 60 each pair of rails increased conductivity and a better doweling of the rails for alinement are secured.

In Figs. 29 and 30 is illustrated a further modification of this type of bond, consisting 65 of the additional provision of a lining *m* for

the plug so that a metal, such as aluminum, which is not subject to oxidation, may be used for the pair's which slide on each other, and a copper core may be employed to secure greater conductivity.

Figs. 35 and 36 show an alternative form of bond, consisting of a bent strip *n*, which is soldered or welded to the rails near their meeting ends. Tie plates *p*, held to the webs of the rails by bolts *q*, keep the rails in alignment. A bond of this type is preferable to the form of bond first described at the ends of sections which may require removal and replacement where it is not possible, owing to rail insulation at each end, to shift the rails 70 endwise sufficiently to take out or assemble with the telescoping form of bond.

In Figs. 37 and 38 the protecting cover is made in three parts, this form being preferable on account of economy in lumber from 85 which the covering is constructed, absence of joints through which water can fall into the spaces between the covering and the rail, and because clamps may be dispensed with. A top strip *r* is chambered to receive the top 90 bulk of the rail, and one of the bottom strips *s s* is nailed in place before assembly on the rail. After hooking the top strip and the bottom strip nailed thereto, onto the rail, the other strip is nailed in place as shown.

In Figs. 39 and 40 is illustrated a three-part holding block, the joints coming at the sides instead of at the top, so that water will be less likely to reach the space between the block and the rail. The parts are mortised 100 together so that the clamp-hook will hold them all in place. Joints in the block are not essential to the invention herein disclosed, as one-piece blocks could be slipped onto the rail from the end, but as some of the available refractory insulating materials, such as reconstructed granite, have little tensile strength, and may crack when clamped in place, they are made in two or more parts in the first instance, thereby determining the 110 position of the joints, preventing chipping at corners and making assembly more convenient.

The invention has been herein illustrated in connection with the well known bulb form 115 of web-rail, but it is likewise applicable to other forms of web-rails and other forms of rails.

What we claim as new and desire to secure by Letters Patent of the United States is:

1. The combination of an under-contact rail, supporting brackets, holding-blocks suspending the rail from the brackets and protecting and insulating the rail at the points of suspension, and a sheathing of 125 bendable insulating material supported by the rail and protecting the rail between the points of suspension, substantially as described.

2. The combination of an under-contact 130

- 5 rail, supporting brackets, holding-blocks of a non-charring moisture-proof material suspending the rail from the brackets and protecting the rail at the points of suspension, 5 and a sheathing of bendable insulating material supported by the rail and protecting the rail between the points of suspension, substantially as described.
- 10 3. The combination of an under-contact rail, supporting brackets, and holding-blocks loosely suspending the rail from the brackets and protecting the rail at the points of suspension, substantially as described.
- 15 4. The combination of an under-contact rail, supporting brackets, holding-blocks of a non-charring moisture-proof material suspending the rail from the brackets and protecting the rail at the points of suspension, and a protecting sheathing of insulating material supported from the rail between the holding-blocks of adjacent brackets, substantially as described.
- 20 5. The combination of an under-contact rail, supporting brackets, holding-blocks of a non-charring moisture-proof material loosely suspending the rail from the brackets and protecting the rail at the points of suspension, and a protecting sheathing of insulating material supported from the rail between the holding-blocks of adjacent brackets, substantially as described.
- 25 6. The combination of an under-contact rail, supporting brackets, holding-blocks of a non-charring moisture-proof material suspending the rail from the brackets and protecting the rail at the points of suspension, and a protecting sheathing of insulating material supported from the rail and abutting against the holding-blocks, substantially as described.
- 30 7. The combination of an under-contact rail, supporting brackets, holding-blocks of a non-charring moisture-proof material supporting the rail from the brackets, and clamp-hooks for holding the blocks to the brackets, substantially as described.
- 35 8. The combination of an under-contact rail, a supporting bracket, holding-blocks of a non-charring moisture-proof material supporting the rail from the bracket, and a clamp-hook for holding the blocks together and against the bracket, substantially as described.
- 40 9. The combination of an under-contact web-rail and protecting strips of insulating material supported from the rail, consisting of a top strip enveloping the top bulb of the rail and side strips secured to the under side of the top strip and engaging the web of the rail, substantially as described.
- 45 10. The combination of upright brackets, holding insulators embracing the rail, supporting arms for the insulators, and an under-contact rail yieldingly carried by the
- 55 arms and insulators from the brackets, substantially as described.
- 60 11. The combination of upright brackets, holding insulators embracing the rail, supporting arms for the insulators, and an under-contact rail yieldingly carried by the arms and insulators from the brackets at one side of the brackets and passing beneath the arms, substantially as described.
- 65 12. The combination of an under-contact rail, brackets, insulators carrying the rail spaced along the same and carried by the brackets, and a detachable sheathing carried by and covering the rail between the insulators, substantially as described.
- 70 13. In a third rail supporting means, in combination, a bracket; two insulating blocks adapted to receive and support the rail between them; and a hook bolt extending over said blocks for securing them to said bracket.
- 75 14. In a third rail supporting means, in combination, a bracket having a bearing face; two insulating blocks adapted to receive and support a rail between them; and a hook bolt adapted to extend over said blocks for securing them to said bearing face.
- 80 15. In a third rail supporting means, in combination, a bracket having a substantially vertically-extending bearing face; two insulating blocks adapted to receive and support the rail between them; said blocks extending over the upper part of said rail; and a hook bolt adapted to extend over said blocks for securing them to said bearing face.
- 85 16. In a third-rail supporting means, in combination, a bracket having a bearing face and a tongue projecting from said face; two insulating blocks, one of said blocks having a groove to receive said tongue and the other block having a recess therein; and a hook bolt, one end of which is adapted to lie in said recess, said bolt being adapted to secure said blocks to said bearing face.
- 90 17. In a third-rail supporting means, in combination, a standard having a bearing face and a tongue projecting from said face, said face having an opening therein; two insulating blocks adapted to receive between them the base and web of the rail, one of said blocks having a groove for the reception of said tongue and the other block having a recess therein; a hook bolt having an extended end adapted to lie in said recess, said bolt extending over said blocks, the other end of said bolt passing through the opening in said bearing face; and a nut having a screw thread engagement with said bolt.
- 95 18. In a third-rail support means, in combination, two brackets; two insulating blocks adapted to receive between them the base and web of the rail, a pair of said

blocks being clamped to each of said brackets; and a protective covering extending from one pair of the said blocks to the other and comprising a cap piece grooved for the reception of the base of the rail, and two longitudinal side pieces extending inwardly from the sides of said cap piece to the web of the rail.

Signed by us at New York city, N. Y., this 25th day of May, 1905.

WILLIAM JOHN WILGUS.
FRANK JULIAN SPRAGUE.
